[57] CLAIM

The ornamental design for a shirt collar, as shown and described.

DESCRIPTION

FIG. 1 is a perspective view of a shirt including the shirt collar of my new design;

FIG. 2 is a front elevational view of the shirt and collar of FIG. 1;

FIG. 3 is a rear elevational view of the shirt and collar of FIG. 1;

FIG. 4 is a side elevational view of the shirt and collar of FIG. 1; and,

FIG. 5 is a side elevational view, similar to FIG. 4, but depicting the inside of the collar.

The broken line showing of the shirt in all views is for illustrative purposes only and forms no part of the claimed design.
